UNITED STATES PATENT OFFICE.

BRUNO ROSENBAUM, OF BERLIN, GERMANY, ASSIGNOR TO WESTINGHOUSE ELECTRIC & MANUFACTURING COMPANY, A CORPORATION OF PENNSYLVANIA.

AERIAL CONDUCTOR FOR WIRELESS TELEGRAPHY AND WINDING APPARATUS THEREFOR.

Application filed August 29, 1921, Serial No. 496,626, and in Germany July 1, 1915.

(GRANTED UNDER THE PROVISIONS OF THE ACT OF MARCH 3, 1921, 41 STAT. L., 1313.)

The present invention relates to antennæ for use on aircraft and reeling devices therefor, and has for its object the provision of means whereby the antenna may be rapidly reeled and unreeled without danger of breaking or severing the antenna conductor and means for determining the length of conductor which is unwound at a given time.

10 In accordance with this invention an antenna reel is provided which is made of insulating material and which is provided with a guard or flange extending over the drum portion of the reel for preventing the antenna conductor from becoming displaced when the reel is rotated at excessive speeds. In order to eliminate the jamming of the reel due to breakage of the conductor, the present invention provides an antenna conductor which is formed by braiding separate strands rather than twisting them, as is the usual practice. If twisted conductor is used and one strand is broken, the strand will unravel along a considerable length of the cable and form kinks and knots in the conductor and cause the reel itself to become jammed. In order to prevent the cable from being severed by sudden excessive strains such as those produced by the whipping of the free end of the cable or the catching of the free end in stationary objects, there is provided a resilient member which will absorb such sudden strains.

35 In using antennæ aboard aircraft it has been found to be highly desirable to know exactly the length of antenna which has been paid out, and this invention therefore provides an antenna conductor marked at convenient intervals, the markings being preferably individual and characteristic, to indicate in themselves the length of cable which is hanging free. It has been found that if a cable of woven structure is used, markers of various colors can be woven in with the cable during the weaving process, and these may be of different colors so that they will visually indicate to the operator the length of cable which is unreeled.

50 A clearer understanding of this invention may be had from the following description of a preferred embodiment which is illus-

trated in the accompanying drawing. In this drawing,

Fig. 1 is a mid-section of a reel having 55 wound thereon an antenna conductor at the end of which is inserted a spring device to absorb sudden strains in the conductor;

Fig. 2 is a fragmentary side view of the reel shown in Fig. 1.

Referring to the drawing, an antenna reel 1, preferably of insulating material, is mounted on a shaft 10, which is supported by means of a bracket 11. A ratchet 6 is securely fastened to the reel 1 and is engaged by a pawl 7, which is preferably supported in the guard 4. This guard is secured to the shaft 10 of the reel and to the standard 11, and is adapted to extend over the reel channel to maintain the antenna conductor in place, especially when the speed of the reel is excessive. An extension 8 on the pawl 7 is provided whereby the pawl may be released from engagement with the ratchet 6 in order to unwind the reel. 70 The reel is preferably wound up by means of a handle 12, although power means may be employed. On this reel is wound the antenna conductor 2 which in itself has no insulating covering, and it therefore becomes important that the reel be made of 75 insulating material. The antenna conductor is preferably braided in order to eliminate any difficulties due to strands breaking and becoming entangled in the mechanism of the reel. Markers such as are indicated at 9 are placed along the length of the antenna conductor and may be of different colors in order to indicate the length of antenna conductor which has been unreeled.

80 In order to insure rapid unwinding of the reel, it is necessary to hang a weight 3 on the end thereof. This weight often becomes broken off due to whipping of the end of the antenna conductor or catching of the weight in the branches of trees and the like. In the reel illustrated in Fig. 1 the weight 3 is attached to the end of the conductor 2 by means of a spring 5, which is adapted to absorb any undue strains in the conductor 2.

100 It will be seen, therefore, that by means of this invention a very rapid unwinding of the conductor is made possible without dan-

ger of the conductor becoming entangled in the reel, and further, the danger of breakage of the antenna conductor itself is reduced because of the provision of the spring means for absorbing the strains.

It is to be understood, however, that the foregoing description of a preferred embodiment is not to at all limit the spirit and scope of this invention, as many modifications will at once be apparent to those skilled in the art.

I claim:

1. In combination with a winding reel for a radio antenna for aircraft, a conductor, a weighted body at the end of said conductor, a resilient member interposed be-

tween said conductor and said weighted body to absorb sudden tensional strains which might otherwise injure said conductor.

2. In combination with a winding reel for a radio antenna for aircraft, a conductor, a weighted body attached to the end of said conductor, a recess in said weighted body containing a helical spring one end of which is fastened to said body and the other end to said conductor for absorbing sudden tensional strains which might otherwise injure said conductor.

In testimony whereof I affix my signature.

BRUNO ROSENBAUM.
